UNITED STATES PATENT OFFICE.

BANKS W. VAN ORMER, OF FOLSOM, PENNSYLVANIA, ASSIGNOR TO WESTINGHOUSE ELECTRIC AND MANUFACTURING COMPANY, A CORPORATION OF PENNSYLVANIA.

TURBINE BLADING.

Application filed August 13, 1923. Serial No. 657,129.

To all whom it may concern:

Be it known that I, BANKS W. VAN ORMER, a citizen of the United States, and a resident of Folsom, in the county of Delaware and State of Pennsylvania, have invented a new and useful Improvement in Turbine Blading, of which the following is a specification.

My invention relates to elastic-fluid turbines, and it has for its object to provide low-pressure blading for apparatus of this character which shall be capable of automatic adjustment to provide better paths for the flow of steam under variable load conditions.

A further object of my invention is to provide one or more rows of stationary low-pressure blades, each of which is capable of flexing transversely in accordance with the velocity of elastic fluid passing therethrough.

In the operation of elastic-fluid turbines it is found that, at light loads, blading at the low-pressure end may abstract little, if any, energy from the elastic fluid owing to the fact that the energy has been very largely abstracted by preceding stages. Under such a condition, reduced velocity elastic fluid acts upon blading of the conventional type in such a way as to reduce the over-all efficiency of the turbine over that which would exist if the inactive blading could be omitted. In accordance with my invention, I provide transversely flexible, stationary, low-pressure blades which are capable of automatic adjustment in accordance with the elastic-fluid velocity so as to provide better paths for the passage of elastic fluid under different operating conditions. In case of normal load, the transversely flexible blades flex due to the impact of elastic fluid to provide curved surfaces such as the normal blade would have for the purpose of properly directing the elastic fluid to the following row of moving blades.

In case the turbine load should drop and the impactive force of the steam against the transversely flexible blades should be sufficiently reduced, the latter blades will automatically straighten out so as to provide paths therebetween which shall permit of the passage of steam with a minimum degree of turning. In other words, it is the object of my invention to

provide low-pressure blading which shall be capable of discharging elastic fluid with a minimum degree of resistance when operating at light loads.

Apparatus made in accordance with my invention is illustrated in the accompanying drawings, forming a part of this application, in which Fig. 1 is a detail sectional view of turbine blading incorporating my invention; Fig. 2 is a sectional view taken along the line II-II of Fig. 1; Fig. 3 is a view similar to Fig. 1, but showing a modified form of my invention; and Fig. 4 is a detail view of a supporting element for use in connection with my improved blading.

Referring now to the drawings for a better understanding of my invention, in Fig. 1, I show a rotor 10 carrying moving rows of blades 11 and 12 and a casing or stator 13 carrying a stationary row of blades 14. The stationary blades 14 constitute the subject of my invention and they will now be described.

The stationary blades 14 are shown being made up of a plurality of hinged sections 15, 16 and 17; and, while I show three such hinged sections, it is to be understood that any suitable number may be employed. The hinged section 15 adjacent to the row of moving blades 11, is provided with inner and outer trunnions 18 and 19 which fit in sockets 20 and 21 provided, respectively, in the inner and outer rings 22 and 23. The rings 22 and 23 are provided with rod portions 24 and 25 which fit in openings 26 and 27 provided in the shroud ring 28 and in the base ring 29, respectively. Springs 30 and 31 are arranged within the openings 26 and 27, respectively, and adjustable abutments 32 and 33 cooperate with the outer ends of such springs so that the degree of compression thereon may be adjusted in order to vary the tendency of the rings 22 and 23 to move toward the moving blades 11.

The sections 17 adjacent to the moving row of blades 12 are provided with trunnions 35 and 36 which fit openings 37 and 38, provided, respectively, in the shroud ring 28 and in the base or holding ring 29.

From the structure described, it will be apparent that the springs 30 and 31 normally tend to move the rings 22 and 23 away from the shroud ring 28 and the base or holding ring 29, respectively, in order to straighten

out the hinged blades as shown by dotted lines in Fig. 2.

The base or holding ring 29 preferably fits against the shoulder 39 on the casing or 5 stator 13 and a filling ring 40 may be used for holding the base or holding ring 29 in position.

The shroud ring 28 is preferably provided with ribs 41 which serve to limit leakage 10 around the inner ends of the hinged blades.

To facilitate manufacture, the rings 28 and 29 are preferably made in sections which are connected together by rigid radial webs 42, as may be seen from Fig. 4.

15 In Fig. 3, I show a further modified form of my invention in which the transversely flexible blades are each made in a single piece, thereby avoiding the hinged construction and the necessity of using two-part, supporting-ring structures. In this view, I show transversely flexible stationary blades 45 carried by inner and outer rings 46 and 47, respectively, the ring 46 serving as a shroud ring and the ring 47 being secured to the stator 13 in a manner similar to the ring 29 already referred to. The blades 45 have inner trunnions 48 and outer trunnions 49 which fit openings 50 and 51, respectively, in the rings 46 and 47, respectively. The entrance sides of the blades 45 are provided with trunnions 52 and 53 which fit slots 54 and 55, respectively, in the rings 46 and 47, respectively. The slots 54 and 55 are of sufficient length so that, when the trunnions 52 and 53 are at the forward ends thereof, the blades 45 completely straighten out. When the trunnions 52 and 53 occupy the rear ends of the slots 54 and 55, the blades 45 are curved transversely. Blades 40 made in accordance with this modification are made of some flexible material, preferably steel, and are necessarily thin enough in cross-section to bend when subjected to the impact of motive fluid.

45 The operation of apparatus made in accordance with my invention is as follows: After passage through the higher pressure stages of the turbine, elastic fluid enters the moving row of blades 11, then passes between the transversely flexible blades 14, of Fig. 1, or 45 of Fig. 3, and then enters between the last row of moving blades 12 from which it is discharged to the exhaust. With sufficiently light loads, steam leaves the 50 moving row of blades 11 at such low velocity that the impactive force thereof against the transversely flexible blades is overbalanced by the effective force of the springs 30 and 31, of Fig. 1, or of the inherent flexibility of the blades 45, of Fig. 3, with the result that the transversely flexible blades straighten out to provide substantially straight paths for the flow of steam therebetween.

55 The transversely flexible blades, therefore, serve to provide paths having mini-

mum resistance to the discharge of elastic fluid from which the available energy has already been substantially removed by the preceding blading. The reason for this is that passing of relatively inert steam in 70 curved paths between stationary blades is avoided. With a sufficient increase in load, the velocity of steam discharged from the row of blades 11 increases; and, with a sufficient velocity increase, the impactive 75 force of the steam acting against the transversely flexible blades, becomes sufficient to cause the latter to assume a normally transversely curved outline in order to present inlet edges at the proper angle for the reception of steam from the blades 11 and to present outlet edges at the proper angle for the discharge of steam for entrance between the blades 12.

80 It is to be understood that the two types of construction for the transversely flexible stationary blades are referred to by way of example only, and that any suitable construction might be used so long as these blades are capable of flexing in this way 85 for the purpose stated.

90 While I have shown my invention in but two forms, it will be obvious to those skilled in the art that it is not so limited, but is susceptible of various other changes and 95 modifications, without departing from the spirit thereof, and I desire, therefore, that only such limitations shall be placed thereupon as are imposed by the prior art, or as are specifically set forth in the appended 100 claims.

105 What I claim is:

1. In a turbine, the combination of a row of moving blades followed by a row of transversely flexible stationary blades.

110 2. In a turbine, the combination of a row of moving blades followed by a row of transversely flexible blades and means for normally exerting a straightening-out influence on the latter.

115 3. In a turbine, a row of stationary blades each of which consists of a plurality of hinged sections, and spring means normally tending to straighten out the sections.

120 4. In a turbine, a row of stationary blades, each of which consists of a plurality of hinged sections, means for supporting the rear section of each blade, and spring means tending normally to move the forward section so as to straighten out the hinged sections.

125 5. In a turbine, the combination of a row of moving blades, a row of transversely flexible blades following said moving blades, and a further row of moving blades following the transversely flexible blades.

130 6. In a turbine, the combination of a row of moving blades followed by a row of transversely flexible stationary blades whose transverse contours from the inlet to the out-

let edges thereof are dependent upon the velocity of motive fluid discharged by the moving blades.

7. In a turbine, the combination of a row 5 of moving blades, a row of stationary transversely adjustable blades following the moving blades and whose transverse contours are dependent upon the velocity of motive fluid

discharged by the moving blades, and further blading following said adjustable 10 blades.

In testimony whereof, I have hereunto subscribed my name this 30th day of July 1923.

BANKS W. VAN ORMER.
